Charles A. Ambrose,

INVENTOR

BY Victor J. Evans & Co.

ATTORNEY

WITNESS:

P. J. Hickey

UNITED STATES PATENT OFFICE

2,021,826

LID FASTENER

Charles A. Ambrose, Ponchatoula, La.

Application November 26, 1934, Serial No. 754,884

2 Claims. (Cl. 292—288)

This invention relates to lid fasteners, and its general object is to provide a fastener that is primarily designed for use in securing the lids or covers of containers, such as baskets, hampers and the like in closed position, and in a manner to prevent casual or accidental displacement or removal, yet the fastener can be easily and expeditiously applied and removed with very little effort.

10 A further object of the invention is to provide a cover fastener that is formed from a single strand of wire, and is independent or completely detachable from the container and its cover, yet can be carried by the latter when not in use.

15 Another object of the invention is to provide a fastener that extends across the cover in contacting engagement therewith, to apply uniform pressure thereto, so as to eliminate casual displacement of the cover and loss of the contents of the container.

20 A still further object of the invention is to provide a cover fastener, that is simple in construction, inexpensive to manufacture and extremely efficient in use and service.

25 This invention also consists in certain other features of construction and in the combination and arrangement of the several parts, to be herein-after fully described, illustrated in the accompanying drawing and specifically pointed out in the appended claims.

30 In describing my invention in detail, reference will be had to the accompanying drawing wherein like characters denote like or corresponding parts throughout the several views, and in which:

35 Figure 1 is a fragmentary view of a container and its cover showing my fastener in use.

Figure 2 is a fragmentary vertical sectional view taken through Figure 1.

40 Figure 3 is a top plan view of the fastener per se.

Figure 4 is an end view thereof.

45 Referring to the drawing in detail, it will be noted that I have illustrated my fastener as securing the cover or lid of a hamper in closed position, but I want it understood that the fastener can be used with covers of other types of containers. The body of the container as shown is indicated by the letter A, the upper hoop by the letter B, while C indicates the cover.

50 My fastener is formed from a single strand of resilient wire into substantially rectangular formation, as best shown in Figure 3, and includes spaced parallel straight side portions 1 and 2 and end portions which are disposed below the plane 55 of the side portions. The end portions include curved intermediate portions 3 that follow the curvature of the body of the container as shown, and formed on the ends of the curved intermediate portions 3 are outwardly projected bulged portions 4 that in turn have formed on the ends

thereof inwardly directed fingers 5 that merge into laterally extending and upwardly curved connecting portions 6 which connect the end portions with the side portions as clearly shown in Figure 1.

5 In the use of my fastener, it is applied to the cover C with the side portions bridging the same, as clearly shown in Figure 1. The cover can then be disposed upon its container and the end portions will be disposed below the hoop B. The fingers 5 are then arranged between the hoop B 10 and the body A, with the result it will be seen that accidental displacement or removal of the cover will be impossible. The outwardly projecting bulged portions 4 not only prevent the fingers from extending a too greater distance between the 15 hoop B and the body A due to the fact that these portions 4 contact with the lower edge of the hoop, but the portions 4 are also used to remove the cover, as it is obvious upon inspection of Figure 1 that when downward pressure is applied to the 20 portions 4, the fingers will be removed from the positions shown. The portions 4 are relatively long, so that they may be easily gripped or acted upon by a tool as will be apparent.

25 It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A fastener for the cover of a container and being formed from a single strand of resilient wire 35 into substantially rectangular formation, said fastener including a pair of spaced parallel side portions adapted to bridge the cover, end portions, laterally extending upwardly curved portions connecting the end portions with the ends of the side portions and disposing the end portions in a plane below the side portions, said end portions including curved portions to follow the curvature of the container, upwardly extending fingers for 40 detachably connecting the end portions to the 45 container and means included in the end portions for disconnecting said fingers.

2. A fastener for the cover of a container, the latter including a body and a hoop disposed about the upper end thereof, said fastener being formed 50 from a single strand of resilient wire and including a pair of spaced parallel side portions to bridge the cover, end portions formed on the ends of the side portions, means included in the end portions for disposal between the hoop and the body for 55 detachably connecting the fastener to the container, means for limiting the movement of the first mentioned means and being adapted for disconnecting the same.

CHARLES A. AMBROSE. 60
